Primary Examiner — Selina Sikder(74) *Attorney, Agent, or Firm* — Harness, Dickey & Pierce, P.L.C.(57) **CLAIM**

The ornamental design for a circuit protection element, as shown and described.

DESCRIPTION

FIG. 1 is a perspective view of a circuit protection element, showing our new design;

FIG. 2 is a front view of a circuit protection element;

FIG. 3 is a back view of a circuit protection element;

FIG. 4 is a left view of a circuit protection element;

FIG. 5 is a right view of a circuit protection element;

FIG. 6 is a top view of a circuit protection element; and,

FIG. 7 is a bottom view of a circuit protection element.

1 Claim, 4 Drawing Sheets(56)
